UNITED STATES PATENT OFFICE.

JAY M. JOHNSON, OF CHICAGO, ILLINOIS.

COIN-RECEIVER FOR FARE-BOXES.

1,116,435.

Specification of Letters Patent. Patented Nov. 10, 1914.

Application filed December 18, 1911. Serial No. 666,388.

To all whom it may concern:

Be it known that I, JAY M. JOHNSON, a citizen of the United States, and a resident of the city of Chicago, in the county of Cook and State of Illinois, have invented certain new and useful Improvements in Coin-receivers for Fare-Boxes; and I do hereby declare that the following is a full, clear, and exact description of the same, reference being had to the accompanying drawings, and to the numbers of reference marked thereon, which form a part of this specification.

In the use of fare boxes on street railways and elsewhere, it has sometimes occurred that a conductor or collector has deposited a coin in the receiving hopper of a size sufficiently large to block the chute, thereby arresting subsequent fares from delivery into the box, and later, when opportunity serves, removing the coin.

The object of this invention is to afford a coin casing having a plurality of delivery apertures therethrough, each of which is of a size to permit coin of the proper denomination to be delivered therethrough, and which arrest a coin of a larger denomination, and the walls of which are so constructed that, should a coin of larger denomination be dropped into position to cover or partly cover one of said discharge apertures, the same will be unstably or tiltingly supported at its edges.

It is a further object of the invention to afford a device of the class described, in which a coin of larger denomination than that for which the device is intended, will be unstably supported therein, so that a coin of the proper denomination falling thereon will tilt the same, permitting said coin to slide therefrom into the box.

The invention is intended particularly for use in connection with a fare box and register of the class embodied in the joint application for patent of Jay M. Johnson and Hugo J. Baur, filed on the 7th day of November, 1910, Serial No. 591,093, though, of course, adaptable for use in connection with fare registers and boxes of any kind or description.

A preferred form of the invention is hereinafter more fully described.

In the drawings: Figure 1 is a central vertical sectional view of a coin hopper casing with my improved coin hoppers therein. Fig. 2 is an enlarged top plan view of the

same. Fig. 3 is a section on the line 3—3 of Fig. 2.

As shown in said drawing, the reference numeral 3 indicates the ordinary receiver adapted to be secured to the top of a fare box, my improved coin hopper casing being also fastened in place thereon over said receiver by means of bolts passing through lugs 4 on said casing. Said casing comprises an upwardly extending, peripheral wall 5, which may be constructed of cast or pressed metal, as preferred, and in the drawings is shown as rectangular, inasmuch as the top of the fare box is rectangular. Fitted within said peripheral wall to afford a tight joint therewith is the hopper plate proper, comprising a downwardly and inwardly conically tapering shell, the bottom of which is pressed or stamped to afford a plurality of inner hoppers, as shown six (6) in number, (although, of course, the number may vary), each of which tapers downwardly to the discharge aperture 6, at its bottom, which is of a size to permit any coin for which the fare box is constructed, to fall freely therethrough and through the receiver 3, into the fare box. The walls of said inner hoppers are each flattened at intervals around the bottom thereof or surrounding the discharge aperture to afford a non-circular discharge aperture, the curvature of said walls for a part of their surface being much greater than the curvature of other parts on each side thereof and at the same level, so that when a coin 7, of a denomination larger than the fare box is intended to receive, is dropped into the fare box, it will lodge therein, as indicated in dotted lines in Figs. 2 and 3, or in other words, will be tiltingly supported in the aperture of the hopper, so that when another coin, for example, the coin 8, indicated in dotted lines in Fig. 3, is dropped thereon, said coin slides therefrom into the coin box.

The operation is sufficiently obvious from the foregoing description. While I have described hoppers, the walls of which are spoken of as non-circular, or as having different curvatures at the same level, it is to be understood, however, that any conformations of said walls, whether provided with concavities or convexities that will be capable of tiltingly supporting the larger coin in the hopper, to permit other coins to slide therefrom into the fare box, are within the scope of this invention.

I have shown but one (and that the preferred) form of my invention, through numerous variations in detail and construction will readily suggest themselves. I therefore do not purpose limiting myself otherwise than necessitated by the prior art.

I claim as my invention:

1. A device of the class described, embracing inwardly tapering walls of irregular contour, the lower edges thereof outlining an aperture also of irregular contour, whereby the same will unstably support a coin larger than said aperture so that a coin smaller than said aperture falling therein will tilt said larger coin to permit said smaller coin to slide therethrough.
- 10 2. A device of the class described, embracing a hopper casing adapted to receive

fares and having a plurality of hoppers arranged in the bottom thereof, each of the latter having inwardly tapering walls of irregular contour, the lower edges thereof outlining an aperture also of irregular contour, whereby the same will unstably support a coin larger than said aperture so that a coin smaller than said aperture falling therein will tilt said larger coin to permit said smaller coin to slide therefrom through said hopper.

In testimony whereof I have hereunto subscribed my name in the presence of two subscribing witnesses.

JAY M. JOHNSON.
